UNITED STATES PATENT OFFICE

PHINEAS A. MILLIS AND MARVIN JOHNSON, OF UXBRIDGE, MASSACHUSETTS

SELF-THREADING LOOM SHUTTLE

Application filed February 9, 1928. Serial No. 253,092.

The invention relates to shuttles used in weaving and to that type of shuttle known as self-threading shuttles, and has for its object the provision of means by which the thread will readily find its way into the laterally directed thread passage, and when the shuttle is finally threaded danger of the thread pulling or flying out of the laterally directed passage is avoided.

10 The invention has particular reference to what is commonly known in the art as the Draper shuttle, an example of which is shown in Patent Number 834,606, of October 30, 1906. In this shuttle the delivery passage 15 or eye of the shuttle is connected with the self-threading mechanism by means of a vertical slot. In the operation of the shuttle at times the thread will pull or fly out of the eye through the vertical slot and runs on the 20 self-threading device and continual occurrences of this action of the thread causes a groove to be worn in the self-threader so that eventually it is necessary to discard it.

In this invention the vertical slot is eliminated and in place thereof a slot inclined to the base of the shuttle is substituted, this slot starting at one end of the eye, preferably the end toward the bobbin recess, thus making it impossible for the thread to pull or fly out 30 of the lateral or transverse passage after the shuttle is threaded, and furthermore the inclined structure of the slot assists in completing the threading of the shuttle as the thread is more easily drawn into the trans- 35 verse passage than through the vertical passage employed in the shuttle referred to.

The invention will be described in detail hereinafter and will be found illustrated in the accompanying drawings in which

40 Figure 1 is a top plan view of one end of a shuttle constructed in accordance with the invention.

Figure 2 is a side view of the same portion of the shuttle shown in elevation, and

45 Figure 3 is a fragmental plan view broken away and shown partly in section.

In the drawings similar reference characters will be used to designate corresponding parts throughout the several views.

The body of the shuttle is designated 1

and has a bobbin recess 2. The self-threading device 3, which may be of any well known construction, is carried by the shuttle, the form shown in the drawings being that of the Draper shuttle hereinbefore referred to, and 55 has a thread slot 4 alined with the thread passage 5 formed by the breast 6 and longitudinal ridge 7 that terminates with a tapered portion 8. The self-threading device has a horn 9 that directs the thread into the thread 60 passage 10, said horn 9 having its base 11 extended over the ridge 7 and contacts with a portion of the body 1 designated 12 forming a continuation of said base 11 and spaced from the tapered portion 8 so that the thread that 65 is threaded into the thread passage 10 by one movement of the shuttle by the reverse movement of the shuttle is moved through the passage 13 formed by the tapered portion 8 and the adjacent portion 12 of the body 1 70 into the transversely directed or extending thread passage 14. The ends of said passage 14 are reinforced by pins 15 of steel or any other preferred material, and 16 is a pin 75 usually employed to take the wear of the thread from the self-threader 3. It will be apparent that by providing the slot 13 at an acute angle to the base 1^a of the bobbin body 1 and making the end of the slot communicating with the transversely directed thread 80 passage 14 as shown in Figure 2, unthreading of the bobbin during operation of the loom will be eliminated.

What is claimed is:—

1. In a self-threading shuttle for looms, the combination with a shuttle body, a threading device having a longitudinal thread passage, and the shuttle body provided with a transversely extending thread passage communicating with said longitudinal thread passage, the body of the shuttle having an unobstructed threading slot communicating with said transversely extending relatively narrow and straight thread passage tangential with respect thereto and at the rear thereof arranged at an acute angle to the base of the shuttle from one end of said passage to prevent casual unthreading of the shuttle. 95

2. In a self-threading shuttle for looms, the combination with a shuttle body, a thread- 100

ing device having a longitudinal thread passage, and the shuttle body provided with a transversely extending unobstructed thread passage communicating with said longitudinal thread passage, the body of the shuttle 5 extended rearwardly over said transversely extending relatively narrow and straight thread passage adjacent the top and rear thereof and tangentially with respect thereto 10 and having the end of said rearwardly extended portion tapered, and the body of the shuttle at the rear of and above said thread passage spaced from said tapered portion forming a threading slot communicating with 15 said transverse thread passage.

In testimony whereof we affix our signatures.

PHINEAS A. MILLIS.
MARVIN JOHNSON.
